UNITED STATES PATENT OFFICE

WILLARD G. MYERS, OF BRONXVILLE, NEW YORK, ASSIGNOR TO LEANDER DEVELOPMENT CORPORATION, OF NEW YORK, N. Y., A CORPORATION OF NEW YORK

DESIGN FOR A HEAT INDICATOR FOR AUTOMOBILES

Application filed April 2, 1932. Serial No. 43,374. Term of patent 3½ years.

To all whom it may concern:

Be it known that I, WILLARD G. MYERS, a citizen of the United States of America, residing at Bronxville, Westchester County, New York, have invented a new, original, and ornamental Design for a Heat Indicator for Automobiles, of which the following is a specification, reference being had to the accompanying drawing, forming part thereof.

The figure is a front elevation of a heat indicator for automobiles embodying my new design.

I claim:

The ornamental design for a heat indicator for automobiles as shown.

In testimony whereof I have signed my name to this specification.

WILLARD G. MYERS.
